UNITED STATES PATENT OFFICE

FRANKLIN C. GIBSON, OF FAIRFAX COUNTY, VIRGINIA, ASSIGNOR TO ELLIOTT-FISHER COMPANY, A CORPORATION OF DELAWARE

SHEET-COLLATING MEANS

Application filed April 12, 1926. Serial No. 101,597.

This invention relates to form collating means and has for its object to facilitate the rapid collation of forms on the platen of a recording or other machine.

5 In the accompanying drawings:

Figure 1 is a transverse section of a portion of the platen and platen frame of the well known Elliott-Fisher billing and book-keeping machine equipped in accordance

10 with my invention.

Figure 2 is a section on the line 2—2 of Figure 1.

Figure 3 is a plan view partly broken away, and

15 Figure 4 is a plan view of a fragment of a form or work sheet.

The depressible flat platen 1 is mounted in a platen frame 2, the side rails of which constitute tracks or guides for travelling printing mechanism and also alignment

20 guides for the forms or work sheets 4. The work sheets are imposed on the platen when the latter is in depressed position and are clamped by the raising of the platen against one or

25 more work clamps 5 extended along one or both of the rails 3. The clamp 5 is usually provided with a line scale 6 which guides the operator in locating the form on the platen since it will be evident that as the travelling

30 recording mechanism has predetermined line positions for the lines of the record, the form must be accurately located in order to properly locate the record with reference to lines or other matter which may be printed on

35 the sheet. This location of the form in accurate position relative to the platen and to any other forms or sheets which may be in use at the same time, requires considerable skill on the part of the operator and con-

40 sumes an appreciable amount of time. The time lost in this sheet collating operation is multiplied many times in the course of a long run of billing.

The purpose of the present invention is

45 to provide means whereby the form may be quickly located in any selected line position and retained during the raising of the platen to firmly clamp the form against the clamp

50 5. To this end the platen 1 carries a form holder or retaining device in the form of

a pressor plate 7 overlying the edge of the platen and drawn down upon the platen by a spring 8 interposed between the under side of the platen and the angular shank 9 of the clamp or pressor plate. The shank 9 is 55 preferably provided with a sleeve 10 slideable upon a screw 11, screwed into and extended below the platen as shown in Figure 1. Preferably this depressing and guiding means for the pressor plate 7 is duplicated 60 as indicated in Figure 2. The mere mounting, on the depressible platen, of this work clamping member 7 constitutes an embodiment of my invention in one aspect since this device without further development 65 would serve to hold a form in its accurately located position while the platen is moving toward the clamp 5. The further development of the invention, however, contemplates the mounting in the platen, below the 70 pressor plate 7, of a form or sheet locator, preferably in the form of a ball 12, mounted in a socket 13 in the platen 1 and yieldingly supported by a light spring 14. To permit the ball 12 to occupy a position slightly 75 projected above the surface of the platen when the pressor plate 7 is in its completely depressed position, or when it is drawn down upon a form, said plate is provided with an opening 15 into which the upper portion of 80 the ball projects.

The form or work sheet 4 is provided with a locating margin in the form of a series of apertures 4^a which, when the edge of the form is against the alignment guide 3, may 85 be brought into registration with the ball 12 by the movement of the form lengthwise of the series of openings. The holes 4^a in the form are spaced apart in correspondence with the spacing of the lines of the record. As the ball or form locator has an accurate location with reference to the positions of the machine, it follows that the form may be quickly located by placing it upon the platen, moving it under the pressor plate 7 and against the alignment guide and then shifting it to the proper line location in which resistance to further movement of the form is opposed by the ball which extends into an opening in the form. Obvi- 105

ously the form may be very quickly located because while it may be readily shifted along the alignment guide due to the fact that the ball will both rotate and yield bodily, the rising of the ball into each of the openings 4^a presents repeated resistance to the movement of the form and apprises the operator when each line position of the form is reached. Furthermore, it is not necessary for the operator to arrest the form in absolutely accurate line location because if the movement of the form is discontinued with the form in approximate, but not accurate, location, it will be cammed into position by the action of the ball seeking to seat itself in the approximately located opening. Obviously this form locating means may be located at either or both sides of the platen, the latter variation being contemplated since it often happens that a plurality of superposed forms or sheets are utilized at the same time and it would obviously be desirable to locate different sheets by means of locators mounted at different sides of the platen.

25 What I claim is:

1. The combination with a flat platen for supporting a form for line spacing movement thereover, of a form provided with openings, and a spring pressed locating ball disposed in the face of the platen to seat in the openings in the form.

2. The combination with a platen, of a spring pressed form locating ball mounted therein, and a pressor plate coacting with the ball to locate and hold the form.

3. The combination with a depressible platen, of a pressor plate overlying one edge of the platen and movable therefrom, and a form locating ball mounted in the platen below the pressor plate to engage a form interposed between the pressor plate and ball.

4. The combination with a platen, of locating means carried thereby including a pair of oppositely yielding male and female members, respectively, designed to engage opposite faces of an intermediate work sheet or form and cooperating to cam the sheet or form relative to the platen.

5. The combination with a platen, of form locating means carried thereby, said means including oppositely yielding coacting members, one of which is in the form of a freely rotatable ball and the other of which is apertured to receive the ball.

6. The combination with a platen, of a work sheet or form having an aligned series of openings, and a pair of cooperating locating members arranged to receive an interposed margin of the form, one of said members having the form of a yielding freely rotatable ball disposed to project into and beyond an opening to cam the form into location, and the other member having a socket receiving the projecting portion of

the ball whereby said socketed member engages the form around the opening.

7. In combination, a flat platen adapted to support for movement thereover a form having marginal openings, and form locating means including cooperating members for gripping the form therebetween one of said members having a convex locating face and being yieldingly mounted to engage said face with one of said openings whereby the form is automatically cammed into location.

8. The combination with a platen adapted to support for movement thereover a form having marginal openings, of form locating means including a convex cam member on the platen disposed to project into and beyond a selected opening in the form to cam the latter into location, and a yielding presser member having an aperture disposed to receive the portion of the cam projecting beyond said form whereby said presser member yieldingly engages the form around said opening.

9. In testimony whereof I have affixed my signature.

FRANKLIN C. GIBSON.
